PULVERIZING APPARATUS

Fred H. Daniels, Worcester, Mass., assignor to
 Riley Stoker Corporation, Worcester, Mass., a
 corporation of Massachusetts

Application June 26, 1931, Serial No. 546,962

2 Claims. (Cl. 83—11)

This invention relates to pulverizing apparatus, and more particularly to machines of the beater type which pulverize material finely by the action of impact or attrition members mounted upon a 5 rotor and arranged to be revolved at a high velocity.

In constructing machines of this type for greater capacities, it has heretofore been the practice to enlarge the diameter of the rotor. At 10 the same time it has been necessary to reduce the speed at which the rotor is driven, in order to avoid dangerous and excessive linear velocities adjacent to its periphery. If the driving motor is directly connected to the pulverizer shaft by 15 means of a coupling, as is frequently the case, this motor must likewise be selected for the lower rotational speed and hence will be more bulky and expensive for a given horsepower than a higher speed motor. Moreover, it is found that if the diameter of a pulverizer of this type is increased, a 20 point is eventually reached where the efficiency begins to decrease, although the efficiency of the driving motor is usually greater the higher its rated horsepower.

25 It is accordingly one object of the invention to provide a pulverizing apparatus of large capacity which is so arranged that it may be operated at a comparatively high rotational speed, and which will reduce material to a desired degree of fineness with a minimum consumption of power.

It is a further object of the invention to provide a pulverizing apparatus which is of compact construction and which will occupy the minimum of space for a given pulverizing capacity.

35 It is a further object of the invention to provide a pulverizing apparatus which is so arranged that all parts subject to wear are readily accessible for renewal.

40 It is a further object to provide a pulverizing apparatus which is simple and inexpensive to manufacture and install.

With these and other objects in view, as will be apparent to those skilled in the art, my invention resides in the combination of parts set forth in 45 the specification and covered by the claims appended hereto.

Referring to the drawings illustrating one embodiment of my invention, and in which like reference numerals indicate like parts,

50 Fig. 1 is a section through a pulverizing apparatus, the section being taken substantially on the line 1—1 of Fig. 2;

Fig. 2 is a section on the line 2—2 of Fig. 1;

Fig. 3 is a section on the line 3—3 of Fig. 1;

55 Fig. 4 is a section on the line 4—4 of Fig. 1;

Fig. 5 is an enlarged sectional view showing the separable joint in the pulverizing chamber wall; and

Fig. 6 is a detail of a stationary peg.

The embodiment of the invention illustrated in 5 the drawings comprises a casing 10 shaped to provide a pulverizing chamber 11 having a peripheral inlet opening 12 for the coarse material and two central outlet openings 14 for the pulverized material. As shown particularly in Fig. 2, the inlet 10 12 leads downwardly into the pulverizing chamber at one side of the vertical axial plane, and extends throughout substantially one quarter of the circumference of the chamber. In an axial direction, the inlet opening is of the same width as the 15 pulverizing chamber. As best shown in Fig. 1, the outlet openings 14 are located directly opposite each other in the side walls of the chamber.

Within the chamber 11 I provide a rotor 15, which is illustrated as a vertical disk arranged to 20 rotate about a horizontal axis. This disk 15 is mounted on a horizontal shaft 16 which extends through the outlet openings 14 and is rotatably supported in bearings 18. A half coupling 19 is shown on one end of the shaft for convenience in 25 connecting a driving motor thereto. Pulverizing elements 21 are mounted on the disk 15. The members 21 illustrated are of the general type disclosed in the patent to Craig, No. 1,714,080, and are shaped as pegs formed integral with segmental wear plates 22. The plates 22 are fastened 30 to the sides of the disk 15 adjacent to the periphery thereof by means of bolts 23. With this construction, the pegs 21 form spaced annular rows 35 on opposite sides of the rotor disk. These pegs 21 preferably extend only part way to the side walls of the pulverizing chamber, so that a free space is provided between these parts through which material of sufficient fineness may flow towards 40 the centrally located outlets 14.

It will be clear that in passing through the pulverizing chamber 11 the material must travel against the centrifugal force set up by the revolving pegs 21. In order to transport the material 45 through the machine against this force, I utilize 45 powerful air currents which may be produced in various ways but which are preferably set up by suction fans connected to the outlet openings 14. In the preferred embodiment illustrated, the casing 10 is extended to provide a fan chamber 25 at 50 each side of the central pulverizing chamber 11, and a fan 26 is mounted on the shaft 16 and arranged to rotate therewith. As shown in Fig. 3, the peripheral wall of each fan chamber 25 is 55 shaped as a volute or scroll leading to a discharge

connection or nozzle 27. Renewable liner blocks 28 of a suitable wear resisting material are mounted around the inside surface of the scroll.

Although in general only the fine particles of material are drawn inwardly by the air current against the centrifugal action of the revolving pegs 21, it is found that particles occasionally reach the outlets 14 which are coarser than is desirable. In order to prevent the escape of such coarse particles into the fan chamber, I provide 10 rejector blades 30 which revolve adjacent to the outlets. These blades 30 are U-shaped in cross section and extend outwardly in substantially radial directions from the shaft 16. In the embodiment 15 illustrated I have shown four rejector blades adjacent to each outlet, and these serve to scoop coarse particles from the issuing cloud of material and hurl them back into the pulverizing chamber. Each set of rejector blades 30 revolves adjacent to a rejector ring 31 which surrounds the shaft. These rings 31 define the outlet openings 14 leading from the pulverizing chamber to the fan chambers.

In addition to the revolving pegs 21, I preferably 25 provide stationary pegs 33 which assist in the pulverization of the material. The pegs 33 are shown arranged in annular rows projecting from both side walls of the pulverizing chamber and extending toward the rotor. Two rows of 30 these stationary pegs are shown at each side of the rotor, and they interfit with the revolving pegs as particularly illustrated in Fig. 1. Each peg is preferably formed with a thin flanged ferrule 34 (Fig. 6) of pressed steel or similar material, as 35 disclosed in the patent to Riley No. 1,576,472. These pegs are supported by two flat annular cheek plates 35, each of which has circular openings therein through which the pegs are inserted. Each plate 35 is formed of two sections held together by straps 36 (Fig. 2) for convenience in 40 assembly.

In order to protect the peripheral portion of the casing from wear, I provide a number of flanged liner plates 38 and 39 which are bolted to 45 the side walls of the pulverizing chamber. These plates extend toward each other and are located in the direct path of material hurled outwardly by the revolving pegs 21. The plates 38 located to the right of the vertical axial plane in Fig. 2 50 have inwardly extending flanges, while the plates 39 located in the lower left portion of Fig. 2 and beneath the inlet 12 have outwardly extending flanges. The casing wall adjacent to these plates 39 is vertical and provided with a door 40 through 55 which access may be had to the plates and their fastening bolts. Below the horizontal axial plane these wear plates are concentric with the rotor, but the plates in the upper right portion of Fig. 2 are arranged on a spiral which approaches the 60 axis in the direction of rotation, the end of the plate directly above the rotor axis being spaced therefrom the greatest distance. This construction is of value in obtaining uniform distribution of the incoming material about the rotor periphery.

Referring now to Figs. 2 and 3, it will be seen that the casing 10 is divided by three axial planes into three separate sections in order to facilitate manufacture and assembly. These sections are 70 formed with cooperating flanges which may be bolted together. The first and lowest section 42 extends throughout an angle of 135 degrees measured from the horizontal axial plane. This section forms the support for the other two, and also 75 carries the discharge nozzles 27, which at instal-

lation are connected by pipes with other apparatus. The second section 43, which includes the feed inlet opening 12, is mounted upon the lower section 42 and extends throughout an angle of 90 degrees measured between the horizontal and vertical axial planes. At assembly the section 43 is connected to the other apparatus which supplies the coarse material to be pulverized, and it is intended that this portion of the casing should remain permanently in place. The third section 10 44 of the casing is fastened to the other two and extends throughout an angle of 135 degrees measured from the vertical axial plane. This section is so arranged that it can be readily removed to give access to the interior of the casing when it 15 is necessary to renew any of the various parts.

In order that the section 44 of the casing may be removed without any interference on the part of the stationary pegs 33, these pegs are mounted on the side walls of the pulverizing chamber 11 20 independently of the removable casing section, the construction in this respect being similar to that disclosed in the patent to Andrews No. 1,840,380 granted January 12, 1932. As illustrated, I provide vertical plates or diaphragms 46 (Fig. 25 1) formed integral with the sections 42 and 43 of the casing, and the rejector rings 31 are bolted to these diaphragms, the lower portions of the rings being separable from the remaining portions as shown particularly in Fig. 2, so that the rings 30 may be slipped into place or removed without disturbing the shaft. The cheek plates 35 are mounted on the rejector rings, and may be rotated thereon by hand to bring the pegs 33 successively into a convenient position for replace- 35 ment.

In the portions 42 and 43 of the casing, the flanges of the pegs 33 are clamped between the cheek plates 35 and the diaphragms 46 by means of cap screws 47, which are readily accessible for 40 turning by a socket wrench when the section 44 of the casing is removed. The pegs 33 adjacent to the section 44 of the casing are held in place by clamping their flanges between the plates 35 and two backing plates 48 by means of cap screws 45 50. The backing plates are each shaped as a circular ring sector having an angle of substantially 135 degrees. A tongue 51 (Fig. 5) is provided along the upper edge of each backing plate, and vertical diaphragms 52 are formed integral with 55 the removable section 44 of the casing and in line with the tongues. These diaphragms, with the liner plates 53 and 54 bolted thereto, form overlapping tongue and groove joints with the backing plates, thus preventing leakage and rendering the side walls of the pulverizing chamber rigid at assembly.

The operation of the invention will now be apparent from the above disclosure. The discharge nozzles 27 are connected by piping to suitable 60 apparatus for utilization or storage of the pulverized material, and the inlet opening 12 is supplied with the coarse material at a controlled rate. In case the material to be pulverized is coal, it is desirable that it first be crushed to a 65 small and uniform size in a suitable hammer mill and all tramp metal removed before it enters the inlet 12. The shaft 16 is rotated at a high speed by a suitable source of power, and the fans 26 produce powerful air currents which flow inwardly through the pulverizing chamber 11 to the outlets 14, and thence through the fan chambers 25 to the discharge nozzles. Particles which are of sufficient fineness are immediately carried along by these currents, while the coarser par- 70 75 76 77 78 79 80 81 82 83 84 85 86 87 88 89 90 91 92 93 94 95 96 97 98 99 100 101 ticles remain in the pulverizing chamber and are reduced to a powder by the action of the rapidly revolving pegs 21 and the stationary pegs 33. Any coarse particles which chance to approach the outlet openings 14 are scooped out of the issuing stream by the rejector blades 30 and hurled back into the pulverizing zone.

The apparatus is of simple construction and inexpensive to manufacture. The casing can be readily fabricated of steel plates welded together. All parts which are subjected to wear can be easily replaced by first removing the casing section 44, and this can be done without disturbing the inlet or discharge connections. Since the rotor is of symmetrical construction, there is no tendency for centrifugal force to cause bending stresses therein, nor is there any unbalanced arrangement which could produce an axial thrust on the driving shaft. The machine may be of large capacity without necessitating a large rotor diameter and it may therefore be operated at a high speed safely, thus permitting the use of an efficient and inexpensive driving motor. The entire construction is very compact and requires a minimum of floor space.

Having thus described my invention, what I claim as new and desire to secure by Letters Patent is:

1. A pulverizing apparatus comprising a casing shaped to provide a pulverizing chamber and a fan chamber at one side of the pulverizing cham-

ber, the pulverizing chamber being connected to the fan chamber by a centrally located passage, a horizontal rotatable shaft extending through the casing, a rotor mounted on the shaft within the pulverizing chamber, impact members on the rotor, and a fan mounted on the shaft within the fan chamber, the fan chamber having a peripheral wall shaped as a scroll leading to a discharge connection adjacent the up-running portion of the fan, the pulverizing chamber having a peripheral inlet opening adjacent the up-running portion of the rotor, and the casing having a removable section located adjacent the down-running portions of the fan and rotor to allow access to the interior of the casing.

2. A pulverizing apparatus comprising a casing shaped to provide a pulverizing chamber, a rotor mounted within the pulverizing chamber and arranged to rotate about a horizontal axis, pulverizing elements on the rotor, the pulverizing chamber having a peripheral inlet located adjacent the up-running side of the rotor and an outlet located adjacent the axis of the rotor, the peripheral wall of the chamber being shaped to form a spiral starting at the inlet and gradually approaching the rotor in the direction of rotation thereof, and means to pass a current of air through the casing to carry the pulverized material through the outlet.

FRED H. DANIELS. 30
